UNITED STATES PATENT OFFICE

JOHN W. BOUGHTON, OF PHILADELPHIA, PENNSYLVANIA.

AIRSHIP.

1,109,658.

Specification of Letters Patent.

Patented Sept. 8, 1914.

Application filed January 4, 1911. Serial No. 600,765.

To all whom it may concern:

Be it known that I, JOHN W. BOUGHTON, a citizen of the United States, residing in the city and county of Philadelphia, State of Pennsylvania, have invented a new and useful Airship, of which the following is a specification.

My invention relates to an air ship and consists of wings for the same formed with means for imparting cyclonic force forwardly against the fronts, and upwardly against the under sides of said wings, whereby great ascending and sustaining power and swiftness are imparted to the ship.

It consists also of means for changing the angle at which the propellers of the ship may be presented to the atmosphere, and furthermore of means whereby the propellers on opposite sides of the ship may be at angles of the same changed independently of each other for purposes regarding the same in the event of the ship swinging or gyting irregularly.

For the purpose of explaining my invention, the accompanying drawing illustrates a satisfactory reduction of the same to practice, but the important instrumentalities thereof may be varied, and so it is to be understood that the invention is not limited to the specific arrangement and organization shown and described.

Figure 1 represents a perspective view of an air ship embodying my invention. Fig. 2 represents a vertical section of a portion on the line $\alpha-\alpha$ Fig. 1. Fig. 3 represents a side elevation of one of the wings of the ship. Figs. 4, 5, and 6 represent side elevations of different forms of wings employed. Fig. 7 represents a perspective view, partly in full, and partly in dotted lines of another form of a wing employed.

Similar letters of reference indicate corresponding parts in the figures.

Referring to the drawings:—A designates the frame of the ship, and B designates a room or cabin house which may be occupied by a suitable motor and other appliances and by the aviator, attendants, passengers, freight, etc.

D designates the driving shaft which is mounted on suitable portions of the frame and adapted to be operated by the motor, and to operate through intermediate gearing the propellers of the ship. A rudder F is also provided, the same having suitable

connections G leading to the room B whereby the former may be operated for steering purposes as usual.

To the frame A are secured the banks of wings H, which consist of plates of light metal or other material arranged comparatively horizontally on the frame and extending transversely thereon. The forward ends of the wings are deflected downwardly and rearwardly forming the crooks or elbows J under which the air may pass for a purpose to be hereinafter described.

As will be clearly seen upon reference to Figs. 1 and 2, the crooks or elbows J extend entirely across from end to end of the plane forming pockets to assist in creating a vacuum underneath the wings. The wings may be staggered as in Fig. 1, or arranged in a right line as in Fig. 5, and they may be right lined or variously elliptical in longitudinal direction, forms of which are shown in Figs. 4, 5, and 6. In Fig. 7, the terminal of the wing is reinforced by the transversely-extending angle bar K which is secured thereto in any suitable manner. On the wings are guards L which consist of plates which rise from the side ends of said wings and serve to prevent lateral deflection of air on the backs of the wings for a purpose to be hereinafter described.

W designates swinging frames which are mounted freely on the shaft D and form the bearings of the shafts which by means of gearing Y cause the rotation of the propellers E.

It will be seen that when the ship is set in motion, the air impinges on the elbows J and the current created thereby is impelled under the elbows and by the current created forcibly impacted forward against the rear of said elbows and upwardly against the under faces of the wings with a cyclonic force. Simultaneously therewith, a vacuum is created by said wings on the backs or upper faces thereof, and thus the wings act to cause ascent and flight of the ship with great ascending and sustaining power and swiftness, and the ship may glide with ease while its descent is controllable so that it may be made gently and with comparative safety, it being noticed that the guards L retain as it were, the vacuum on the backs of the wings between said guards and thus preserve the same and render it effective in its action on the wings.

Having thus described my invention what

I claim as new and desire to secure by Letters Patent, is:—

1. In an airship, a frame, and a bank of wings arranged substantially horizontally thereon and disposed transversely, each wing having its forward end deflected downwardly and rearwardly, its upper face inclined downwardly and rearwardly, and guards at the opposite edges of the upper face of said wing extending substantially vertically.
2. In an airship, a frame, and wings secured thereto in banks disposed transversely across said frame in different horizontal planes, each wing having vertical transversely disposed guards to prevent lateral deflection of the air on the backs of the wings, said wings having inclined upper surface and provided with an elbow upon its under face.
3. In an airship, a frame and wings secured thereto in banks disposed transversely across said frame in different horizontal planes, each wing having thereon a downward deflection presented to the front and extended rearwardly beneath the body of the wing forming elbows upon their under faces to direct air beneath said wing and impact it forwardly on the back of said deflection, said wings having inclined upper

surfaces and upwardly extended means upon their upper faces on opposite sides, to retain vacuums on the upper faces of the wings and to prevent lateral deflection of the air on the backs of said wings.

35

4. In an airship, a wing having thereon a downward deflection presented to the front and extended rearwardly beneath the body of the wing to direct air beneath said wing and impact it forwardly on the back of said deflection, said wing being reinforced within its front terminal and upon its upper face provided with vertical guards at opposite edges thereof.

40

5. In an airship, a wing having thereon a downward deflection presented to the front and extended rearwardly beneath the body of the wing to direct air beneath said wing and impact it forwardly on the back of said deflection, the terminal of said wing having a transverse reinforce therein, said wing being provided with vertical guards at opposite edges thereof, the upper face of the wing being inclined downwardly and rearwardly.
